CLAIM

The ornamental design for a compact disc player, as shown and described.

DESCRIPTION

FIG. 1 is a front elevational view of a compact disc player showing my new design;

FIG. 2 is a left side elevational view thereof, the right side being a mirror image;

FIG. 3 is top plan view thereof;

FIG. 4 is a front elevational view thereof, in an open condition; and,

FIG. 5 is a right side elevational view thereof, in an open condition.

The rear views of the compact disc player in an open or closed condition, the top view of the compact disc player in an open condition, and the left side elevational view of the compact disc player in an open condition form no part of the claimed design.
